[57] CLAIM

The ornamental design for a combined massager and massaging heads, as shown and described.

DESCRIPTION

FIG. 1 is a rear end perspective view of the combined

massager and massaging head shown in FIG. 5 with the massaging head removed;

FIG. 2 is a side elevational view thereof;

FIG. 3 is a side elevational view thereof rotated 90 degrees;

FIG. 4 is a front end elevational view of the massager; FIG. 5 is a side elevational view showing the first embodiment of the combined massager and massaging head, showing my new design;

FIG. 6 is another side elevational view of FIG. 5;

FIG. 7 is a front end elevational view thereof;

FIG. 8 is a side elevational view of a second embodiment of the combined massager and massaging head;

FIG. 9 is another side elevational view of FIG. 8;

FIG. 10 is a front elevational view thereof;

FIG. 11 is a side elevational view of a third embodiment of the combined massager and massaging head;

FIG. 12 is another side elevational view of FIG. 11;

FIG. 13 is a front elevational view thereof;

FIG. 14 is a front end elevational view of the first massaging head;

FIG. 15 is a rear end elevational view thereof;

FIG. 16 is a front end elevational view of the second massaging head;

FIG. 17 is a rear end elevational view thereof;

FIG. 18 is a front end elevational view of the third massaging head;

FIG. 19 is a rear end elevational view thereof;

FIG. 20 is a rear end perspective view of the first embodiment;

FIG. 21 a rear end perspective view of a third embodiment;

FIG. 22 is rear end perspective view of the second embodiment; and,

FIG. 23 is a rear end elevational view of the massager.
